US0D1024839S

(12) **United States Design Patent** (10) Patent No.: **US D1,024,839 S**
(45) Date of Patent: ** Apr. 30, 2024

(54) **HYDROPONIC PLANTER**

(71) Applicant: **Starmex Innovations Technology (ShenZhen) Co., Ltd**, Shenzhen (CN)

(72) Inventors: **Wei Dong**, Shenzhen (CN); **Chengye Cao**, Shenzhen (CN)

(73) Assignee: **Starmex Innovations Technology (ShenZhen) Co., Ltd**, Shenzhen (CN)

(**) Term: **15 Years**

(21) Appl. No.: **29/874,835**

(22) Filed: **Apr. 26, 2023**

Related U.S. Application Data

(62) Division of application No. 29/854,809, filed on Sep. 28, 2022, now Pat. No. Des. 988,185.

(30) **Foreign Application Priority Data**

Mar. 29, 2022 (CN) 202230167539.1

(51) LOC (14) Cl. **11-02**

(52) U.S. Cl.

(57) **CLAIM**

The ornamental design for a hydroponic planter, as shown and described.

DESCRIPTION

FIG. 1 is a front perspective view of a hydroponic planter, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the hydroponic planter, which form no part of the claimed design.

1 Claim, 8 Drawing Sheets
